To all whom it may concern:

Be it known that I, HARRY A. Figure 1 is a side elevational view of a vehicle constructed in accordance with my new design;

Figure 2 is a front elevational view thereof, and

Figure 3 is a top plan view thereof.

The essential feature of my design consists in the general outline and shape of the body which suggests a low, graceful, stream-like effect.

I claim:

The ornamental design for a commercial vehicle substantially as shown and described.
